Patented June 18, 1918.

UNITED STATES PATENT OFFICE.

FRED L. WILLIAMS, OF SAN FRANCISCO, CALIFORNIA.

COMBINATION IGNITION AND FUEL-INJECTING SYSTEM.

1,269,989.

Specification of Letters Patent. Patented June 18, 1918.

Application filed February 26, 1916, Serial No. 80,867. Renewed February 26, 1918. Serial No. 219,342.

To all whom it may concern:

Be it known that I, FRED L. WILLIAMS, a citizen of the United States, residing at the city and county of San Francisco and State 5 of California, have invented new and useful Improvements in Combination Ignition and Fuel-Injecting Systems, of which the following is a specification.

This invention relates to a combination ignition and fuel injecting system, particularly adapted for use in connection with internal combustion engines of the "Diesel" type.

The object of the present invention is to 10 provide a novel method and apparatus for injecting and igniting fuel in internal combustion engines.

The invention consists of the parts and the construction and combination of parts 15 as hereinafter more fully described and claimed, having reference to the accompanying drawings, in which—

Figure 1 is a central, vertical section through the combination igniter and injector.

Fig. 2 is a cross section on line 2—2 of Fig. 1.

Referring to the drawings in detail, A indicates the head of an internal combustion engine; 2 the cylinder proper; and 3 the piston. Adapted to be screwed into the cylinder or head, so as to communicate with the compression space formed between the cylinder head and the piston, is a casing 4, 20 provided with a central, longitudinal opening 5 and a water jacket around the upper end.

Suitably secured in the central chamber 5 is a porcelain tube 6, which will herein- 25 after be termed the ignition tube. The lower end of the ignition tube is provided with two sets of annularly disposed spray openings 7 and 8 which communicate with annular channels 9 and 10 formed in the 30 lower end of casing 4. These channels are in turn connected, through a vertical passage 11, with a fuel receiving chamber 16 to which fuel is admitted through a pipe 13 connected with a pump or other suitable 35 means (not here shown).

Mounted in the lower end of the casing 4 is a pair of needle valves 14 and 15. The valve 14 is adapted to close communication between the vertical passage 11 and the annular channel 9; and the valve 15 is adapted 40 to enter the passage 11 to regulate the vol-

ume of fuel passing therethrough into the lower channel 10, as will hereinafter be described.

The upper end of the central passage 5 45 is enlarged on one side to provide a space 16 between the ignition tube 6 and the casing, and the lower end of this enlarged space is extended to form communication, as at 17, with the outer end of the firing chamber 60 12. The upper end of the ignition tube is provided with an annular channel 18, in which is mounted a heating coil 19. This coil is connected with a source of electric current supply (not here shown) through 65 70 means of an insulated plug 20 which extends through the top of the casing, as shown. One terminal of the coil connects with the centrally insulated terminal 21 of the plug and the opposite terminal of the 75 coil connects with the metal portion of the plug. A low tension current passing through the plug and the coil causes the ignition tube to become sufficiently heated to ignite any fuel injected therein, and this 80 heat may be regulated to prevent pre-ignition by regulating the volume of water passing through the cooling jacket, or by other means hereinafter to be described.

Extending through one side of the casing 85 4 and communicating with the interior upper end of the ignition tube is a spray nozzle 23. This nozzle is provided with two connections 24 and 25; the connection 24 being connected with an oil pump or other 90 suitable source of fuel under pressure (not here shown), and the connection 25 with a water pump or other suitable source of water under pressure (not here shown).

The operation will be as follows: When 95 the piston 3 returns, on the compression stroke, a small volume of hydrocarbon fuel will be injected through connection 24 and nozzle 23 into the upper end of the ignition tube; the firing chamber 12 having previously been charged with a heavier grade of fuel during the exhaust stroke of the piston or during the beginning of the compression stroke before any appreciable compression has been created within the cylinder. 100 The small amount of lighter grade fuel injected through the nozzle 23, when the piston reaches the highest point of compression, causes combustion to take place in the upper end of the tube. The expansion, 105 caused by the admitted and ignited charge, is transmitted through the upper end of the

- 2
- ignition tube and the enlarged passage 16, with connected lower passage 17, to the outer end of the firing chamber 12 and causes sufficient pressure at this point to force the fuel charge out of the chamber 16 and down into the vertical passage 11, from where the fuel is permitted to discharge either through the upper spray openings 7 or the lower spray openings 8, or 5 possibly through both sets of spray openings. The needle valves 14 and 15 permit either set of spray openings to be used or the volume of fuel passing therethrough to be regulated to a nicety.
- 10 15 The combination igniter and injector constructed as here shown is particularly adapted for use in connection with internal combustion engines of the "Diesel" type. This arrangement also permits a fine or 20 coarse spray to be produced and will, in this manner, permit a slow burning of the admitted fuel charge or fast burning of same. The small charge of fuel first admitted through the nozzle 23 not only creates the 25 pressure required for the complete expulsion of the main fuel charge from chamber 12 but also causes this to be ignited as it enters the main compression chamber of the cylinder. The timing of ignition and spraying of 30 the main fuel charge is controlled entirely by the fuel pump which connects with the spray nozzle 23, and, as this forms no particular part of the present invention, it is not here illustrated. Any suitable means 35 may be provided for advancing or retarding the stroke of this pump.
- The water connection 25 applied to the nozzle 23 is provided for the purpose of admitting a small amount of water for the 40 purpose of partly cooling the ignition tube should this have a tendency to overheat and pre-ignite, and the cooling of the tube may further be assisted by regulating the volume of water passing through the cooling jacket.
- 45 50 55 60 65 The method and apparatus for igniting and injecting the fuel here shown obviates the necessity of pumping the main fuel charge through the spray nozzle against the high compression of the main combustion chamber, as the oil or fuel supplied to chamber 16 may be pumped in during the exhaust, suction stroke or the first portion of the compression stroke and the fuel may be discharged from the charging chamber 16 at any time desired by adjusting the stroke of the fuel pump connected with the nozzle 23. It also obviates the high pressure air compressors necessarily used with most types of "Diesel" engine now employed and will also to a more or less extent do away with the high compression needed in "Diesel" engines, as the ignition is in this instance caused by the heat of the ignition tube.
- Not only can heavy oils and light oils be sprayed in this manner but the device as a
- whole can be used to advantage on gas and producer gas engines. The device may be used as an ignition system alone, or it may be used for the purpose of enriching the gas mixture already admitted to the cylinder 70 through the inlet valve of the engine; the enriching taking place by permitting a small amount of fuel to be admitted through chamber 16 and its connected spraying passages or through the upper spray nozzle 23. 75 The pressure or other gas employed is in this manner enriched to any point desired and the power and speed of the engine consequently increased. The device may also be used in case of a rich mixture in the combustion engine to spray into the chamber a certain amount of water so as to prevent ignition of the gas mixture by a hot piston or by too high compression. This water would preferably be pumped into the pipe 80 that is used as the main fuel pipe indicated at 13 and would be injected through the spray openings 7 and 8 by an explosion of the character described caused in the upper end of the ignition tube. 85
- The materials and finish of the several parts of the device may be such as the experience and judgment of the manufacturer may dictate. 90
- I wish it understood that various changes 95 in form, proportions and details of construction may be resorted to within the scope of the appended claims and that I do not wish to limit myself to the specific design and construction here shown. 100
- Having thus described my invention, what I claim and desire to secure by Letters Patent is—
1. The method of injecting and igniting fuel in engines of the "Diesel" type which comprehends the injection in different chambers of two fuel charges, igniting one of said charges, and utilizing the pressure and heat thus obtained to drive the other charge into the main combustion chamber and simultaneously igniting said charge. 110
  2. A method of injecting and igniting fuel in internal combustion engines, which consists in injecting into a reception chamber a charge of fuel during a time interval 1 in the movement of the piston when the pressure in the cylinder is low, and then injecting into a primary combustion chamber a charge of fuel to generate sufficient pressure to drive the main fuel charge out of the temporary receiving chamber into the main compression chamber and to ignite the said charge, and accordingly driving the main fuel charge into the main compression chamber and igniting the same. 120
  3. A method of injecting and igniting fuel in internal combustion engines, which consists in injecting into a temporary reception chamber provided with spray openings a charge of fuel during a time interval 1

- in the movement of the piston when the pressure in the cylinder is low, and then injecting into a primary combustion chamber which communicates with the temporary fuel
- 5 reception chamber and the main compression chamber of the cylinder a small charge of fuel to generate sufficient pressure to drive the main fuel charge out of the temporary receiving chamber into the main compression chamber and to simultaneously ignite the said charge.
- 10 4. A combination fuel injector and igniter, comprising a casing having a central chamber formed therein which is adapted to communicate with the compression chamber of an internal combustion engine, a temporary fuel receiving chamber formed in the casing, a hot tube in the central chamber, means for injecting a small charge of fuel into the hot tube, and means for utilizing the pressure caused by the burning of the small charge to inject a main fuel charge previously injected into the temporary fuel receiving chamber.
- 15 5. The combination with an internal combustion engine, of a casing having a fuel receiving chamber formed therein adapted to be charged during a time interval in the movement of the piston when the pressure is low, and means for injecting and igniting a second small charge of fuel to produce sufficient pressure to inject the main fuel charge into the engine cylinder and simultaneously ignite the same.
- 20 6. A combination fuel injector and igniter, comprising a casing having a central chamber formed therein which is adapted to communicate with the compression chamber of an internal combustion engine, a temporary fuel receiving chamber formed in the casing, a hot tube in the central chamber, means for injecting a small charge of fuel into the hot tube, means for utilizing the pressure caused by the burning of the small charge to inject a main fuel charge previously injected into the temporary fuel receiving chamber, means for heating the hot tube, and means for cooling the hot tube.
- 25 7. A combination fuel injector and igniter, comprising a casing having a central chamber formed therein which is adapted to communicate with the compression chamber of an internal combustion engine, a temporary fuel receiving chamber formed in the casing, a multiple set of spray openings communicating with said fuel chamber, means for injecting a main fuel charge into said chamber, means for regulating the flow of fuel through the multiple spray openings, means for injecting a small fuel charge into the hot tube, and means for conveying the pressure generated by the burning of the small charge to the temporary fuel receiving
- 30 chamber to force the main fuel charge out through the multiple spray openings into the compression chamber of the engine and to simultaneously ignite said charge.
- 35 8. A combination fuel injector and igniter, comprising a casing having a central chamber formed therein which is adapted to communicate with the compression chamber of an internal combustion engine, a temporary fuel receiving chamber formed in the casing, a multiple set of spray openings communicating with said fuel chamber, means for injecting a main fuel charge into said chamber, means for regulating the flow of fuel through the multiple spray openings, means for injecting a small fuel charge into the hot tube, means for conveying the pressure generated by the burning of the small charge to the temporary fuel receiving chamber to force the main fuel charge out through the multiple spray openings into the compression chamber of the engine and to simultaneously ignite said charge, an electric heating coil connected with a source of current supply mounted in the upper end of the hot tube to heat same, and means for cooling the hot tube.
- 40 9. A combination fuel injector and igniter for internal combustion engines comprising a casing having a chamber adapted to communicate with the compression end of an engine cylinder, means for introducing a fuel charge into a part of said chamber during a period of low pressure in the engine cylinder, and means independent of any suction effect caused by the engine piston for forcing at least a large portion of said charge out of said chamber and igniting said charge.
- 45 10. A combination fuel injector and igniter for internal combustion engines comprising a casing having a tubular chamber adapted to communicate at one end with the compression end of an engine cylinder, a temporary fuel receiving chamber having free communication with the other end of said tubular chamber and also with an intermediate portion thereof, means for introducing a main fuel charge into said fuel receiving chamber, and means for introducing and igniting an igniting charge near said other end of the tubular chamber to thereby force said main fuel charge into the intermediate portion of the tubular chamber and them into the engine cylinder.
- 50 In testimony whereof I have hereunto set my hand in the presence of two subscribing witnesses.
